NURSING BOTTLE

Ernest A. Panetti, Downingtown, Pa.

Application November 25, 1955, Serial No. 548,988

5 Claims. (Cl. 215—11)

This invention relates to nursing bottles, and more particularly has reference to a valve means insertable into a bottle of this type, designed to insure a steady flow of milk regardless of the position of the bottle.

In many instances, the steady flow of liquid from a nursing bottle is stopped, due to the presence of a partial vacuum within the bottle or to other causes, including tilting of the bottle in which the nipple is at a higher elevation than the lower end thereof, so as to no longer be filled with milk flowing into the same from the main portion of the bottle.

Under these circumstances, not only must frequent attention be given to the infant to insure that there is a substantially continuous flow of milk, but further, the infant may tend to swallow air, causing discomfort and, in many instances, a colic condition.

The main object of the present invention is to provide an improved device insertable in a generally conventional nursing bottle, having check valves at opposite ends of an inlet tube connected in communication with a main tube extending to the nipple, said check valves being so arranged as to insure a flow of milk into the main tube regardless of the bottle position.

Another object is to provide a device as stated which can be readily disassembled to facilitate cleaning and sterilizing thereof.

A further object of importance is to so form the device as to permit it to be used in association with a conventional glass nursing bottle, and with a conventional nipple.

Other objects will appear from the following description, the claims appended thereto, and from the annexed drawing, in which like reference characters designate like parts throughout the several views, and wherein:

Figure 1 is a longitudinal sectional view through a nursing bottle formed according to the present invention, in which the bottle is in an upright position;

Figure 2 is a transverse section on line 2—2 of Figure 1;

Figure 3 is a longitudinal sectional view on a reduced scale in which the bottle is inclined with the nipple projecting upwardly;

Figure 4 is a view like Figure 3 in which the bottle is fully inverted; and

Figure 5 is a view like Figure 3 in which the bottle is inclined with the nipple projecting downwardly.

At 10 there has been designated a transparent container comprising a conventional component of a nursing bottle. Container 10 has a large diameter mouth, closed by a disc 12 of plastic material. Threadable onto the neck of the container is a retaining ring 14 also of plastic material having an inwardly directed peripheral flange 16 bearing against the outwardly directed circumferential flange 18 of a nipple 20. The retaining band forces the nipple flange and the marginal part of the disc 12 against the adjacent end of the container, to sealably engage these components with the container in position closing the mouth thereof.

The device constituting the present invention includes an elongated, straight main tube 22 formed of a transpar-

ent plastic in a preferred embodiment of the invention. Tube 22 extends approximately half the length of the container, in closely spaced, parallel relation to the longitudinal center line of said container. At its outlet end tube 22 is threaded into a complementarily threaded opening 24 formed in disc 12. At its inlet end the tube has a lateral extension 26 communicating freely with the mid-length portion of an inlet tube 28 extending parallel to the tube 22 at the opposite side of said longitudinal center line.

At its opposite ends, the inlet tube has check valve assemblies, said assemblies being of separable construction to facilitate cleaning of the component parts of the device. One of said assemblies includes an elongated, cylindrical valve housing having rounded ends one of which is formed by a cup-like enlargement 30 formed on tube 28 and threaded for engagement with a mating, cup-like enlargement 32. Enlargement 32 is formed on one end of an end section 34 of the inlet tube, and said section 34 at its inlet end is disposed in closely spaced relation to disc 12.

There is thus defined an elongated chamber 36 for a globular check valve element 38 adapted to seat in a tube-closing position against the base of either enlargement 30, 32 respectively.

The middle section of the inlet tube, at its opposite end, has a similar enlargement 40 threadably connected to a complementary enlargement 42 formed upon a second end section 44 of the inlet tube. The cup-like, connected enlargements 40, 42 form a second, elongated chamber 46 for a second valve element 48.

In the disc 12, there is formed a small opening in which is seated a spring-loaded check valve 50, said element 50 controlling the admission of air to the inside of the bottle and being normally biased to a closed position.

In use, and assuming for example that the bottle is upright as in Figure 1, if the infant draws upon the nipple, there will be initially created a vacuum condition within the nipple, and this will cause a flow of the liquid upwardly through the lower end section 44 of the inlet tube. The valve element 40 will accordingly be unseated to permit the passage of the liquid through the lower portion of the inlet tube, and the liquid will now flow through the main tube into a nipple. The upper check valve element 38 in this position of the bottle will gravitate to a position closing the upper end of the inlet tube.

If the bottle is tilted as in Figure 3 with the nipple still facing upwardly, the operation will be the same as in Figure 1. In other words, in every instance in which the nipple is at a level higher than that of the remaining liquid in the bottle, the flow will be from the lower end of the inlet tube and thence to the nipple.

If the bottle is fully inverted as in Figure 4 or inclined with the nipple facing downwardly as in Figure 5, the end portion of the inlet tube that is adjacent the disc 12 will be disposed within the liquid. Under these circumstances, the liquid will flow into section 34, unseating valve element 38, and will then flow through the main tube to the nipple with valve element 48 in a seated position.

It will be understood, in this regard, that the check valve 50 opens automatically whenever necessary to admit air to the interior of the bottle to replace liquid drawn out of the bottle while the infant is feeding. However, said air will under no circumstances enter the flow passage comprising the inlet and main tubes, due to the fact that that end of the inlet tube that is out of the liquid will always be closed by a check valve element. For example, in Figure 1 air tending to enter the inlet tube through section 34 will be prevented from doing so by the seated valve element 38. In Figure 5 the same functional characteristic obtains due to the seating of element 48 in the exposed condition of section 44.

The device, further, can be readily cleaned, since it

can be detached in its entirety from disc 12 and then separated at the valve housings to permit removal of the valve elements and the cleaning of all portions of the inlet and main tubes.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. A nursing bottle comprising a container for a liquid; a disc adapted to close said container at one end; a nipple seating upon the disc; means holding the nipple and disc in sealable engagement with said end of the container; an inlet tube within the container having its opposite ends opening upon the interior of the container adjacent opposite ends of the container; check valve means in the opposite end portions of the inlet tube so arranged that one of said means will admit liquid to the interior of said tube when the adjacent end of the inlet is immersed in the liquid with the other check valve means preventing the admission of air into the other end of the inlet tube; a main tube freely communicating at its opposite ends between the interior of the nipple and the intermediate portion of the inlet tube; and check valve means in the disc arranged to permit flow of air into said container.

2. A nursing bottle comprising a container for a liquid; a disc adapted to close said container at one end; a nipple seating upon the disc; means holding the nipple and disc in sealable engagement with said end of the container; an inlet tube within the container having its opposite ends opening upon the interior of the container adjacent opposite ends of the container; check valve means in the opposite end portions of the inlet tube so arranged that one of said means will admit liquid to the interior of said tube when the adjacent end of the inlet is immersed in the liquid with the other check valve means preventing the admission of air into the other end of the inlet tube; a main tube freely communicating at its opposite ends between the interior of the nipple and the intermediate portion of the inlet tube; and check valve means in the disc arranged to permit flow of air into said container, said check valve means of the inlet tube comprising elongated valve housings communicating at opposite ends with adjacent portions of the inlet tube, said ends of the valve housings providing valve seats, and floating valve elements freely shiftable between opposite ends of said housings for engagement, in different positions to which the container is shifted, against the valve seats of the respective housings.

3. A nursing bottle comprising a container for a liquid; a disc adapted to close said container at one end; a nipple seating upon the disc; means holding the nipple and disc in sealable engagement with said end of the container; an inlet tube within the container having its opposite ends opening upon the interior of the container adjacent oppo-

site ends of the container; check valve means in the opposite end portions of the inlet tube so arranged that one of said means will admit liquid to the interior of said tube when the adjacent end of the inlet is immersed in the liquid with the other check valve means preventing the admission of air into the other end of the inlet tube; a main tube freely communicating at its opposite ends between the interior of the nipple and the intermediate portion of the inlet tube; and check valve means in the disc arranged to permit flow of air into said container, said check valve means of the inlet tube comprising elongated valve housings communicating at opposite ends with adjacent portions of the inlet tube, said ends of the valve housings providing valve seats, and floating valve elements freely shiftable between opposite ends of said housings for engagement, in different positions to which the container is shifted, against the valve seats of the respective housings, said inlet tube being of sectional formation and being separable at locations intermediate the ends of the respective valve housings to facilitate removal of said valve elements and cleaning of the housings and tubes.

4. A nursing bottle comprising a container for a liquid; a disc adapted to close said container at one end; a nipple seating upon the disc; means holding the nipple and disc in sealable engagement with said end of the container; an inlet tube within the container having its opposite ends opening upon the interior of the container adjacent opposite ends of the container; check valve means in the opposite end portions of the inlet tube so arranged that one of said means will admit liquid to the interior of said tube when the adjacent end of the inlet is immersed in the liquid with the other check valve means preventing the admission of air into the other end of the inlet tube; a main tube freely communicating at its opposite ends between the interior of the nipple and the intermediate portion of the inlet tube; and check valve means in the disc arranged to permit flow of air into said container, the inlet tube and main tube extending in parallelism with each other and with the longitudinal center line of said container.

5. A nursing bottle comprising a container for a liquid; a disc adapted to close said container at one end; a nipple seating upon the disc; means holding the nipple and disc in sealable engagement with said end of the container; an inlet tube within the container having its opposite ends opening upon the interior of the container adjacent opposite ends of the container; check valve means in the opposite end portions of the inlet tube so arranged that one of said means will admit liquid to the interior of said tube when the adjacent end of the inlet is immersed in the liquid with the other check valve means preventing the admission of air into the other end of the inlet tube; a main tube freely communicating at its opposite ends between the interior of the nipple and the intermediate portion of the inlet tube; and check valve means in the disc arranged to permit flow of air into said container, the inlet tube and main tube extending in parallelism with each other and with the longitudinal center line of said container, at opposite sides of said longitudinal center line.
